UNITED STATES PATENT OFFICE.

WILHELM SIMMELBAUER, OF MUNICH, GERMANY.

SAFETY RAZOR.

Application filed February 3, 1925. Serial No. 6,598.

To all whom it may concern:

Be it known that I, WILHELM SIMMELBAUER, a citizen of the German Republic, residing at Munich, Bavaria, Germany, have 5 invented certain new and useful Improvements in Safety Razors, of which the following is a specification.

Safety razors have become known which comprise a comb adapted to be adjusted in 10 vertical direction in a U-shaped bow in order to sharpen and strop the razor blade. The blade of a razor of this type can have only one cutting edge and it must be turned 180° when it has to be stropped on the 15 strop situated outside the lever. Owing to the necessity to turn the blade 180° it must be of special construction so that two-edged blades cannot be used for these safety razors.

20 According to the invention a stationary bridge as support for the blade is arranged between the comb and the cover plate on the bow, the razor strop being adapted to be inserted into the safety razor after the comb 25 has been withdrawn.

An embodiment of the invention is shown, by way of example, on the accompanying drawing.

Fig. 1 shows the improved safety razor 30 in front elevation, and

Fig. 2 in side elevation.

The comb or guard *a* vaulted as usual is composed of two parts connected the one with the other at the middle by a bottom 35 plate *b*. The bottom plate is slightly depressed from the plane of the side guards *a* whereby the latter will straddle a bridge, hereinafter referred to. The comb *a* is guided in a U-shaped bow *c* so that it can be adjusted in vertical direction by means of a screw spindle *d* swiveled to the bottom 40 plate and screwed into a threaded bore of the handle *e*, a sleeve-like head *f* of the spindle projecting from the end of the handle *e* serving to operate said spindle. The bow *c* carries a bridge *g* which has two studs *h* and serves as support for the leaf-shaped blade *i* which is covered by a vaulted cover 45 plate *k* hingedly fixed by means of hinges *l* and adapted to be locked in the covering position by a locking hook *m* or the like in order to securely hold the blade *i*.

When the instrument is to be used for 50 shaving, the comb or guard *a* is pushed upward by rotation of the screw spindle *d* until it bears against the blade *i* and presses

the same into the cavity of the cover plate *k* the bridge *g* being received between the two halves of the comb. The blade is thus bent in upward direction. For sharpening or 60 stropping the blade the comb *a* is screwed down so that between it and the blade a sufficiently large interval is formed designed to receive the stropping strap *n* on which the blade is stropped by being moved to and fro. 65 As, owing to the vaulted cover plate *k* the blade is always bent it possesses the elasticity required for stropping when it is adjusted at an angle with regard to the surface of the strop. After both edges of the blade 70 have been stropped on one side, the cover plate *k* is raised, the blade reversed or turned over, the cover plate again lowered and the opposite side of both edges then stropped. 75

I claim:

1. A safety razor comprising in combination a hollow internally threaded handle, a comb composed of two parts, a bottom plate connecting with one another the two parts of said comb, a screw spindle swiveled at 80 the upper end to said bottom plate and screwed into said handle so that its lower end projects from the lower end of said handle, a U-shaped bow on the handle and in which said comb is guided, a bridge secured to the bow, a two-edged blade resting on said bridge, and a cover plate hingedly fixed on the upper end of said handle and covering said blade the comb being adapted to be pulled back from said bridge by means of said screw spindle to 85 form an interval under said bridge into which a strop for stropping the blade is to be inserted.

2. A safety razor comprising a tubular, internally threaded handle, a U-shaped bow supported thereon, a bottom plate extending between the arms of the U-bow and guidingly embracing the same, a screw spindle swiveled to the plate and threaded through the handle, spaced guard elements secured to the plate, a blade-supporting bridge supported by the arms of the U-bow and adapted to be straddled by the spaced guard-elements when the bottom plate is moved upwardly toward the bridge, and a cover plate arranged above the bridge. 95

3. A safety razor comprising a U-shaped bow, a bridge secured to and between the arms of the U-bow for supporting a blade, a cover plate hinged to the upper end of one arm for swinging into overlying relation to 100 105 110

the bridge, a catch pivoted for detachably connecting the free end of the cover plate to the companion arm of the U-bow, said cover plate being bowed transversely, and a 5 movably mounted guard member having a central depression to receive the bridge and permit the lateral guard portions pressing the blade on the bridge up into the bowed cover plate.

4. A safety razor according to claim 3 10 wherein the catch is pivoted to the free end of the cover plate and has an inwardly extending hook part for engaging in an opening in the companion arm of the U-bow.

In testimony whereof I affix my signature.

WILHELM SIMMELBAUER.
